UNITED STATES PATENT OFFICE.

ROBERT GUNTER AND MARSHALL McILWAINE EAKIN, OF LONDON, ENGLAND, ASSIGNEES TO GEORGE THOMAS CAVENDISH PAGET AND WILLIAM EDMUND SLAUGHTER, BOTH OF LONDON, ENGLAND.

EXPLOSIVE PROJECTILE.

1,211,936.

Specification of Letters Patent.

Patented Jan. 9, 1917.

Application filed November 24, 1915. Serial No. 63,167.

To all whom it may concern:

Be it known that we, ROBERT GUNTER and MARSHALL McILWAINE EAKIN, subjects of the King of Great Britain and Ireland, residing respectively, at London, England, have invented Improvements in or Relating to Explosive Projectiles, of which the following is a specification.

The object of the present invention is to provide explosive projectiles better adapted than those heretofore employed for purposes such as the attack of air craft. For this purpose an explosive projectile according to the invention comprises a shell having a wall surrounding a space constituting a central chamber, and formed with housings radiating from the said central chamber, means for subdividing such chamber in an axial direction to form separate explosion regions, explosive charges disposed in said regions, shrapnel bullets in the wall housings, and means for closing the outer ends of such housings, the ultimate destruction of the shell after the bullets have been successively discharged being effected by a high explosive within a base container.

As will be understood, the invention may be carried into effect in various ways, although it has not been thought necessary to illustrate more than one construction in the accompanying drawings, with the aid of which the invention will now be further described.

Of these drawings Figure 1 is a longitudinal section of the shell without the fuse. Fig. 2 is a part transverse section.

As here shown, the shell body *a* is bored radially so as to produce a series of rows of pockets *b* and a series of similar pockets *c* arranged in staggered relationship to the pockets *b*. These pockets *b* *c* contain spherical bullets *d* confined exteriorly by suitable means such as plugs *e* of alloy which may be soldered or pressed into the holes from a sheet of solder for example. The center of the shell is bored to receive explosive charges *e* which may be of black gun powder in a suitable wrapping, the respective charges being separated by metal disks *f* perforated at *g* and held in proper spaced relationship by rings *h* of a more or less skeleton character so that the rows of holes *b*, *c* communicate with the separated explosion regions.

The upper and under side of each disk *f* may have a disk *i* of muslin attached thereto to cover the perforations *g*, such disks *i* being secured in any suitable way such as for instance by shellac. The time fuse is or may be secured by a socket *j* as ordinarily, *h* being a perforated steel or other disk screwed into place before the fuse socket *j* is fitted. The bottom *m* of the shell may be solid and have a gas ring such as *n* applied to it in known way, but it may, as shown, have a perforation *o* placing the last charge compartment in communication with the interior of a base container *p* charged with a high explosive and screwed or otherwise attached to the shell body, *a*, the gas ring *n* in this case being conveniently arranged to engage both the body *a* and the container *p*. The skeleton formation of the rings *h* may be obtained by boring them simultaneously with the holes *b* *c* in the body *a*. It may be advantageously arranged that the grain of the metal of which the container *p* is made shall run transversely thereof with the object of preventing pressure in the gun being communicated by percolation of the gas produced through the grain of the metal so to the explosive in the shell.

What we claim is:—

1. An explosive projectile comprising a shell having a wall surrounding a space constituting a central chamber, and formed with housings radiating from the said central chamber, means for subdividing such chamber in an axial direction to form separate explosion regions, explosive charges disposed in said regions, shrapnel bullets in the wall housings, and means for closing the outer ends of such housings.

2. An explosive projectile comprising a shell having a wall surrounding a space constituting a central chamber and formed with housings radiating from the latter, perforated disks adapted to be inserted in such chambers, rings adapted to be assembled alternately with the disks and hold the latter in spaced relationship thereby forming separated explosion regions, explosive charges disposed in such regions, shrapnel bullets in the wall housings, and means for closing the outer ends of such housings.

3. An explosive projectile comprising a hollow shell having a pierced cylindrical

wall, shrapnel bullets housed in such piercings, charges, adapted to be fired successively, arranged in such hollow shell and a container at the base of the shell adapted to receive a higher explosive than that in the shell, the said container, being in communication with the interior of the shell through a perforation.

Signed at London, England, this 10th day of November, 1915.

ROBERT GUNTER.
MARSHALL MCILWAINE EAKIN.
